(57) **CLAIM**

The ornamental design for a multi functional smith half rack, as shown and described.

DESCRIPTION

FIG. 1 is a first perspective view of a multi functional smith half rack showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion 9 in FIG. 1;

FIG. 10 is an enlarged view of the selected portion 10 in FIG. 2; and,

FIG. 11 is an enlarged view of the selected portion 11 in FIG. 2.

The dash-dash broken lines shown in the drawings depict portions of the multi functional smith half rack that form no part of the claimed design. The dot-dash broken lines in FIGS. 1, 2, 9, 10 and 11 illustrate the periphery of the enlarged views of the multi functional smith half rack and form no part of the claimed design.
